METHOD OF MANUFACTURING ELECTRON
DISCHARGE DEVICESWarley L. Parrott, East Orange, N. J., assignor to
Westinghouse Lamp Company, a corporation of
Pennsylvania

Application October 26, 1929, Serial No. 402,559

1 Claim. (Cl. 250—27.5)

This invention relates to electron discharge devices and more particularly to electron discharge devices incorporating an electron emitting hot cathode of the indirectly heated type, the heater element of which is energized by an alternating electric current, and specifically relates to an improved type of heater element employed in said cathode, and to the method of manufacturing the same. This invention is an improvement in the inventions set forth in copending application Serial No. 292,116 filed July 12, 1928 and application Serial No. 372,331 filed June 20, 1929 by John W. Marden and Ernest Anton Lederer, which applications are assigned to the same assignee as the present invention.

In copending application Serial No. 292,116 above identified is disclosed an electron discharge device incorporating an electron emitting hot cathode of the indirectly heated type, in which is employed a coil type heater element energized by electric current. In order to prevent deleterious electrical discharges from the heater element to the cooperating electrodes of the device a dielectric shield member is interposed between the heater element lead wires and said cooperating electrodes.

In the specific embodiment disclosed the cathode is comprised of a tubular metal sleeve member having an exterior coating of electron emitting material, refractory insulating end plug members, lead wires extending through the end plug members, and a centrally disposed coil type heater element electrically connected to said lead wires.

An electron discharge device incorporating this type cathode in accordance with the specific embodiment therein, has the cooperating electrodes concentrically arranged about the cylindrical sleeve member of the cathode.

In order to prevent deleterious overheating of the interposed control electrode which would cause undesirable electron emission from said control electrode it is customary and desirous to employ a perforated or mesh type anode, the openings in such an anode allowing of greater heat radiating or heat dissipating properties than in a solid electrode. In such an electrode structure one lead wire of the heater element in the cathode must extend a portion of its length adjacent the exterior surface of the anode in order to be electrically connected to the upper end of the coil type heater element. During operation of the device it is found that electrons flowing from the cathode to the perforated anode are precipitated through the perforations and are attracted

to the lead wire carrying the alternating electric current, creating thereby deleterious "hum" characteristics in the plate circuit of the device employing the same. By the interposition of a dielectric shield between the lead wire and the anode this source of deleterious electric discharge is eliminated.

It has been found, however, that another source of deleterious hum is obtained from the heater element itself, as is set forth in copending application No. 372,331 above identified, and is caused by the thermionic activity of the said heater element at the temperature of operation. This source of hum is eliminated in accordance with the invention of this copending application by reducing the temperature of operation of the heater element to below the temperature of active electron emission therefrom supplying thereto at this temperature the desired wattage of electrical energy to heat by radiation the enclosing tubular metal sleeve member to a temperature at which the exterior coating of thermionic material efficiently operates.

It is found, however, that a third source of "hum" is caused by the deleterious electrical effects incident to the use of alternating electric current in energizing the cathode heater element, which source is mainly what is known as an electro-static effect produced in the cathode sleeve member by electric currents induced or produced therein by the coiled heater element through which the alternating electric current flows.

This electrical effect may be substantially eliminated in the cathode of the present invention by a proper spacing of the centrally aligned heater element from the tubular metal sleeve member which may be obtained by increasing the internal diameter of the said sleeve member. The rule appears to be that the closer the spacing, or coupling as it is more commonly spoken of, the greater this electro-static effect, the greater the spacing the less the "hum."

In radio tube manufacture the specific spaced relationship of the incorporated elements or electrodes, relative sizes, and the like dimensional measurements pronouncedly affect the electrical characteristics of the device. In present day electrical circuits, such as radio circuits, employing such devices, certain electrical characteristics as are likely to be affected by such spacing and size of incorporated electrodes are rigidly specified and adhere to. This makes it necessary to limit the spacing of heater element and cathode sleeve member in order to keep within the desired electrical characteristic limits and as a consequence

complete elimination of the undesirable electrical disturbance as a result of inductive coupling between heater element and sleeve member may not be obtained in this manner.

5 It is one of the objects of this invention to eliminate the undesirable electrical disturbances in an electron emitting hot cathode of the indirectly heated type caused by deleterious electrical currents induced in the cathode sleeve member by an alternating current energized helical heater element.

10 It is another object of this invention to provide an indirectly heated cathode having a heater element energized by alternating electric current, 15 in which the diameter of the sleeve member and the specific spaced relationship of heater element and sleeve member may be widely varied without deleteriously introducing undesirable electrical disturbances.

20 Another object of this invention is to provide an electron discharge device incorporating an indirectly heated cathode having a heater element energized by alternating electric current and at least one cooperating electrode, in which the 25 specific spaced relationship of said cathode and heater element and said cooperating electrode may be widely varied without the introduction of deleterious electrical disturbances or effects commonly characterized as "hum" during operation 30 of the device.

35 Another object of this invention is to provide a cathode assembly of the indirectly heated type, the heater element of which is energized by alternating electric current, in which inductive coupling between said heater element and the remaining elements of said cathode is substantially 40 eliminated.

45 These and other objects of the invention will become apparent as the invention is more fully disclosed.

50 In accordance with the objects of my invention I have found that I may substitute for the usual coil type heater element heretofore employed, in an indirectly heated cathode, a non-inductively wound heater coil, constructed and electrically insulated in accordance with the process herein-after disclosed, which in combination with the dielectric shield feature of copending application Serial No. 292,116 and the low temperature operating heater element feature of copending application Serial No. 372,331 above identified, permits the use of the mesh plate electrodes desired for the purpose of cutting down the internal heating effects and permits greater flexibility in the 55 spacing of the elements of said cathode and of the cooperating electrodes in an electron discharge device such as has not heretofore been possible to obtain, thereby producing an electron discharge device in which the deleterious hum characteristics have been reduced to a substantial unmeasurable amount.

60 Before further disclosing the nature of my invention reference should be had to the accompanying drawing setting forth the elements of the present invention, wherein

65 Fig. 1 is an enlarged side elevational view of a non-inductively wound twin coil helical heater element constructed in accordance with the present invention;

70 Fig. 2 is an enlarged side elevational view of an assembled cathode with the tubular metal sleeve member cut away, and with the end plug members and the dielectric shield members shown 75 in cross-section;

Fig. 3 is a side elevational view partly in cross-section of a radio tube mount incorporating the cathode shown in Fig. 2, with the cooperating electrodes cut away to show the spaced relationship of the elements;

75 Fig. 4 is a side elevational view of a 3-electrode radio tube of the type known to the trade as a 227 tube incorporating the features of the present invention, with the enclosing glass envelope partly broken away; and

10 Fig. 5 is a side elevational view of a 4-electrode radio tube of the type known to the trade as a 224 tube or screen grid tube incorporating the features of the present invention with the enclosing glass envelope partially broken away and the cooperating electrodes partly in cross-section to show the spacing of the elements of the device.

15 The twin coil winding of the non-inductive helical heater element of the present invention, illustrated in Fig. 1, is of the type commonly known in the electrical art and has heretofore been variously employed in that art where a neutralization of induced electrical currents in a coil of wire energized by alternating current is desired. Application of this non-inductive winding principle has not heretofore been made in the heater element art, or to the heater element of indirectly heated electron emitting cathodes, or to electron discharge devices incorporating such 20 indirectly heated cathodes.

25 In accordance with the present invention I form the heater element as shown in Fig. 1 of a refractory metal filament 1, preferably of tungsten which is of a predetermined and selected size and length, to conform with the electrical 30 and physical characteristics desired. This length of filament is then bent in the shape of a hairpin, the center loop portion engaged in a slot in the end of a mandrel of the desired diameter, and the two ends of the wire wound about the mandrel in parallel spaced relationship the desired 35 number of turns.

40 The specific pitch to the turns and number of turns employed per inch depends upon the particular type cathode sleeve into which it is to be incorporated, the diameter and length of the heater element wire, and other factors. In winding the coil each set of two turns of the wire are spaced equidistant from the next set of two turns while the two wires of each particular set 45 are equidistant from each other. This relative arrangement of the twin coil filament gives the 50 maximum non-inductive effect.

55 In the present instance, an indirectly heated cathode which is applicable in the 227 type radio tube shown in Fig. 4, is indicated in enlarged view in Fig. 2. The tubular metal cathode sleeve member 2 is approximately 120 to 140 mil in diameter and about 14.5 millimeters in length and has an exterior thermionic electron emitting 60 coating 3 of about 9.0 millimeters length.

65 It is desirable to wind the helix of the coil in such manner that the bulk of the heating effect of the coil is produced within the sleeve member adjacent to this external coating 3.

70 In the specific embodiment shown the twin coil heater element 1 is comprised of approximately 6.5 mil tungsten filament, preferably of the so-called non-sag type. At this diameter the length requisite to give a current consuming capacity or resistance at the required 2.5 volts operation voltage is 13.5 millimeters. To properly position this length filament within the cathode sleeve member so that the maximum heating effect may be obtained I prefer to form the twin 75

coil upon a mandrel of about 25 mil diameter winding the twin turns spaced about 1.0 millimeter having 10 twin turns of 20 single turns, or a rating of 20 double turns per inch or 40 single turns per inch.

To insure the retaining of the turns of the twin coil in proper spaced relationship, I mount the twin coil heater element upon a core of refractory material of substantially the same approximate diameter as the mandrel upon which the coil is wound, properly positioning the coil thereon, and then subject the filament to an anneal operation such as by passing the mounted coil through a high temperature heat zone, preferably in a non-oxidizing atmosphere for the requisite time interval to effect the removal of work hardening effects. I have found that tungsten coils are thus annealed when heated to 1400° C. for a period of about 15 minutes.

The annealed coil and refractory insulating core is then removed from the furnace and the exterior surface of the wire sprayed with a coating of refractory insulating material suspended in an organic binder such as amyacetate-nitro cellulose admixture, after which the assembly of helical filament, core and coating is again baked at about 1400° C. for a few minutes to drive off the binder of the coating and to consolidate the refractory insulating coating to the surface of the wire. The refractory coating thus applied is about .004 inch thick, and weighs in the neighborhood of about 10 milligrams per coil.

The specific composition of the refractory insulating core and sprayed coating, may be widely varied depending upon the refractory metal employed, the desired operating temperature of the filament and the like factors. I have found that a substantially pure aluminum oxide, Al_2O_3 to which has been added a small proportion of fritting agent, such as talc, is most suitable for the purposes of the present invention.

This particular insulating material is disclosed in application by C. V. Iredell, Serial No. 308,139, filed September 24, 1928, now Patent 1,838,766, which application is assigned to the same assignee as the present invention. The core may be prepared by the extrusion method of forming refractory insulators which has heretofore been disclosed in application by J. W. Marden and F. H. Driggs, Serial No. 233,543 filed November 16, 1927 which application is also assigned to the same assignee as the present invention.

I may, however, employ refractory insulating material in forming the core and in coating the wire of a composition of materials such as set forth in application by F. H. Driggs, Serial No. 306,291, filed September 15, 1928, now Patent 1,826,510. The most satisfactory coating for most purposes as well as the most inexpensive and readily applied is talc, chemically identified as magnesium silicate. This compound may be readily purchased upon the market in a state of fair degree of purity and under the temperature conditions of operation of the present type heater element is sufficiently refractory for all practical purposes, and has the desirable dielectric property at that operating temperature.

The completed annealed and insulated twin coiled helical heater element thus prepared is then ready for mounting in the cathode element of an electron discharge device, as is shown in Fig. 2. The particular method of mounting the heater element in the cathode, and the manner of assembling the same with the cooperating elec-

trodes of a radio tube of the 227 type is specifically shown in Fig. 3.

The usual stem tube 18 is employed having at one end a flare (not shown) which is adapted to be sealed to an enclosing glass envelope and at the other end a press or seal portion 15 through which extend leading in support wires 9, 10, 11, 12 and 13, two of which, 12 and 13 respectively, extend beyond the press a sufficient distance to serve as supporting members for the electrode structure of the device. A refractory insulating dielectric shield member, preferably comprised of sheet mica in round disc form approximately $1\frac{1}{8}$ inches in diameter having suitable perforations to permit support wires 12 and 13 to extend therethrough is securely mounted upon the support wires 12 and 13 by means of welding the sleeve portion of eyelets 7, 7 to the support wires allowing the collar of the eyelet to serve as rests or supports for the mica disc. The cathode element including the tubular metal sleeve member 2, and plug members 4, 4 and centrally aligned insulated twin coil helical heater element 1, with the apex engaged by refractory metal guide member 5 extending through upper end plug member 4, is then positioned on the lower dielectric shield member 6, the filament terminals 23 and 24 extended through an opening in the shield 6 and welded to the current conducting lead wires 9 and 10 in the manner shown.

The cathode sleeve member 2 is then electrically connected to the lead wire 11 through an opening in the mica disc member 6, and the cooperating control electrode 16 and plate electrode 17 suitably mounted concentric to the cathode and electrically connected to the leading-in support wires 12 and 13 respectively.

A second dielectric insulating (mica disc) member 8 is then positioned at the top of the assembly of elements and rigidly united to lead wires 12 and 13 in an analogous manner to that employed with the first disc, openings being provided therein for an extension of the grid or control electrode to extend therethrough and for the filament guide member 5 to extend therethrough. A guide sleeve 45 member 19 consisting of a refractory metal eyelet with the sleeve thereof positioned with its longitudinal axis concentric with the axis of tubular sleeve member 2 is provided in the dielectric shield member 8 through which the filament guide member 5 extends, so that the said member may be rigidly united by arc or spot welding the guide member thereto to assist in the positioning and aligning of the twin coil helical filament 1. It is preferable that the two dielectric shield members 5 and 8 should compressively engage end plug members 4, 4 of the cathode so as to assist in the positioning of the cathode in the assembly and that means be provided so that lateral displacement of the elements as a result of shock and vibration be reduced to a minimum.

This method of assembly of the cathode and cooperating electrodes in this type tube in addition to eliminating deleterious electrical discharges heretofore causing undesirable hum noises, also materially reduces losses in manufacture due to assembly defects. The structure is substantially unified and the elements once assembled retain their mounted positions and spacings throughout subsequent manufacturing operations and operating life, and moreover the assembly is substantially free from deleterious microphonic noises caused by mechanical vibrations in loosely held parts.

As an illustration of the extent of the material

advantage obtained by the use of this type cathode in the 227 type cathode such as is disclosed in copending applications Serial Nos. 292,116 and 372,331 above identified, a radio tube constructed in accordance with the practice of the copending application has an average minimum hum value of about 2.0 millivolts. By the use of the present type cathode and heater element, maintaining all other factors constant, the "hum" characteristics have been reduced to less than $\frac{1}{10}$ of a millivolt, which is substantially negligible, and only measurable by an exceedingly sensitive hum tester employing an oscillograph.

The heating up time of the cathode may be varied somewhat depending upon the desired operating temperature of the filament. Due to the fact that the twin coil helical heater element is insulated the heat absorption of the insulating material must be compensated for by a slightly higher operating temperature in the filament. In order to effect an increase in the operating temperature of the filament a smaller diameter filament may be employed. A relatively slight decrease in filament diameter very effectively changes the heating up time of the cathode by raising the operating temperature of the filament a marked degree. The operating temperature of the filament, however, must be maintained below the temperature of active electron emission therefrom in accordance with the invention of copending application 372,331 above identified.

In electron discharge devices of the 224 or screen grid type employing indirectly heated cathodes, the replacement of the heretofore employed insulated hairpin type heater element by the twin coil type insulated helical heater element of the present invention does not substantially effect a material alteration in the spacing of elements in the cathode structure heretofore employed or in the spaced relationship of the electrodes thereto.

In Fig. 5 is shown a side elevational view of this type of tube with the electrode structure partially in cross-section to illustrate the spaced relationship of said elements. In this type tube the cathode sleeve member of the cathode instead of being 120 mil to 140 mil diameter in the 227 type tube is approximately 64 mil to not over 90 mil, depending upon the particular tube characteristics desired. It is desirable to employ in each a heater element having substantially identical current consuming properties. It is also desirable for manufacturing economy to employ in each type tube heater elements which are substantially identical in size, shape, diameter, length, etc.

Heretofore this type tube has employed indirectly heated cathodes of the old type wherein there is interposed between the cylindrical cathode sleeve member and a hairpin shaped heater element a refractory insulating core, the heater element being threaded through openings traversing the longitudinal axis of the core.

The prolonged heating up time, the required high operating temperature of the heater element, and the difficulty of eliminating by dielectric shields the deleterious electric discharges characterized by "hum" sounds in the device during operating the same, were disadvantages which are entirely overcome by the insertion in said cathode sleeve member 2 of the present type non-inductive twin wound insulated helical cathode heater element, in the place of the old type heater.

In Fig. 5 may be seen heater element 1 in position in sleeve member 2, with control grid 20, screen grid 21, and plate electrode 22 concentrically aligned thereto. By the insertion of the twin coil heater element of the present invention in the cathode of the 224 type screen grid tube the heating up time of the cathode has been lowered from approximately 40 seconds as with old type heater to between 5 and 6 seconds, and at the same time, without altering the regular assembly of elements heretofore employed, the "hum" characteristic has been reduced from about 10 millivolts to not over 1.0 millivolt, under standard test conditions.

It is apparent from the above description and the attached drawing that there may be many applications and adaptations made of the specific type of non-inductive twin wound insulated helical heater element in electron discharge devices employing a hot cathode of the indirectly heated type without essentially departing from the nature and scope of the present invention as set forth in the following claim.

What is claimed is:

An electron discharge device comprising an envelope having a press, a circular mica disc spaced from said press, a circular mica disc spaced from said first disc, two support rods sealed in said press, said discs having openings therein through which said rods project, eyelets in said openings for positively engaging said rods and resting on said discs, an anode, cathode and grid located in the space between said discs, said grid being connected to one of said supporting rods, and said anode being connected to the other of said supporting rods.

WARLEY L. PARROTT.
